UNITED STATES PATENT OFFICE.

CLAYTON M. JONES, OF JAMESTOWN, NEW YORK.

RADIATOR.

1,255,173.

Specification of Letters Patent. Patented Feb. 5, 1918.

Application filed September 30, 1915. Serial No. 53,218.

To all whom it may concern:

Be it known that I, CLAYTON M. JONES, a citizen of the United States, residing at the city of Jamestown, in the county of Chautauqua and State of New York, have invented certain new and useful Improvements in Radiators, of which the following, taken in connection with the accompanying drawings, is a specification.

10 The invention relates to radiator cores for cooling the water in motor driven vehicles; and the object of the improvement is to provide a strong and durable zigzag water way construction in which said water ways are not choked at any point but are substantially of the same capacity in cross section throughout their length, yet the sheet metal strips forming said water ways are shaped so as to fit onto one another with broad 15 supporting contact surfaces and strong guiding shoulders which insure the quick and easy assemblage of the parts in an exceedingly strong bracing construction; and the invention consists in the novel features 20 and combinations hereinafter set forth and claimed.

25

In the drawings, Figure 1 is a front elevation of the radiator of a motor car showing the diamond shaped air flues there-through. Fig. 2 is a horizontal crosswise sectional view of one of the water ways. Fig. 3 is an enlarged front elevation of a portion of the core of the radiator showing the construction and arrangement of the 30 same; and Fig. 4 is a vertical crosswise sectional view of a portion of the core of the radiator further showing the construction and arrangement of said radiator core. Fig. 5 is a perspective view of a portion of 35 one of the sheet metal strips forming the side walls of the water ways showing the conformation of the same.

40

Like numerals of reference refer to corresponding parts in the several views.

45 The numeral 10 designates the radiator casing and the numeral 11 designates the core of the radiator. The casing 10 has the reservoir 12 in its upper portion above the core 11 and the reservoir 13 beneath the core 50 11 in the lower portion of the casing 10, the heated water from the motor being received in the reservoir 12 and passing down

through the water ways 14 of the radiator core to the reservoir 13 and from thence to the motor.

55 The core 11 of the radiator is made up of the zigzag water ways 14 which form diamond shaped open ended air flues 15 therebetween when a plurality of said water ways are assembled together. The water ways 14 are each formed by a pair of similarly bent up sheet metal strips 16 which are shaped by a suitable die in the alternating or zigzag form shown so as to provide a practically unobstructed water way 14 60 therebetween, that is, one which has substantially the same volume in cross section throughout its length though said water way is full of zigzag bends and shoulders.

65 The metal strips 16 of each water way 70 have their edges 21 offset toward one another and joined to form a fin of double thickness and provide edge reinforcement for said water way. Broad, transversely extending, flat contact surfaces 17 are offset 75 adjacent each zigzag bend to lie in the same plane as the offset fins 21.

70 The conformation of the flat contact surface 17 in the same plane as the fin or flange 21 provides a relative narrow angular guide 80 shoulder 18 along the inner edge of said contact surface 17 of a height equal to the amount of the offset at 21. The contact surfaces of one water way seat on those of the adjacent water ways when assembled, 85 the shoulders 18 overhanging the outer edges of the opposing contact surfaces to thereby form a strong interlocking joint between the two strips of the water ways 90 which gives great rigidity to the entire construction. The contact surfaces 17 at each bend are preferably placed in opposing pairs so that they converge toward one another with a wedging contact.

95 The thin metal strips 16 have their inner bends 19 offset to conform to the shape of the outer contact surface 17 and shoulder 18 thereby to provide substantially the same volume through the length of the water way 14 therbetween. This arrangement leaves 100 the flanges 21 of the opposite strips 16 in the same plane so that said flanges 21 may be dipped into the acid and solder baths, the solder extending up into the joint between

- each of the contact surfaces 18 and attaching both ends of the same firmly so that said surfaces 17 are strong and rigid in their holding contact upon one another.
- 5 Thus, there is afforded a large radiating surface around the air flues 15 and an unobstructed water way of increased length having larger capacity from the upper reservoir 12 to the lower reservoir 13.
- 10 The mouths 23 of the water ways 14 both at the upper and lower ends of said water ways are preferably enlarged by the recurring angular formation, which arrangement permits the two sheet metal strips 16
- 15 being bent up by the same die, since the bends and shoulders in each are the same. The sheet metal strips 16 are preferably attached to one another at their upper and lower ends by means of the return bend 20 joints 20 though any other means of attachment of these ends would not depart from the invention.

This simple core construction with the water ways 14 having the converging contact surfaces 17 and shoulders 18 is still further braced by means of the joined edges 21 which brace against one another at the bends 22, as shown in Fig. 3, giving added stiffness to the contact joints formed by 30 the contact surfaces 17 and shoulders 18.

It is apparent also that in radiator cores in which it is not necessary to deliver a large amount of water therethrough, the

water ways 14 may be alternated with single zigzag separating strips 16 shaped in substantially the same conformation as for one of the sides of the water way 14.

I claim as new:

In a radiator, pairs of metal sheets formed to provide vertical series of air flues each 40 of approximately diamond shape in cross-section, the intermediate corners of the diamond shaped flues being provided with substantially L-shaped offsets which face downwardly and the top and bottom ends of two 45 adjacent diamond shaped flues being connected by substantially Z-shaped parts formed by contacting relatively wide extensions of the pairs of plates which project beyond said top and bottom ends of 50 the air flues, the air flues of the respective series being arranged in relatively staggered relation with said L-shaped offsets of one series disposed opposite to and spaced from the Z-shaped parts of the adjacent series to 55 provide water passages of substantially equal width throughout, said Z-shaped extensions forming shoulders to hold the plates against upward or downward movement.

In testimony whereof I have affixed my signature in the presence of two witnesses.

CLAYTON M. JONES.
